UNITED STATES PATENT OFFICE.

EDWARD A. WOLFE, OF INDIANOLA, IOWA.

TRUNK-FILLER.

1,092,235.

Specification of Letters Patent.

Patented Apr. 7, 1914.

Application filed April 15, 1913. Serial No. 781,361.

To all whom it may concern:

Be it known that I, EDWARD A. WOLFE, a citizen of the United States, and resident of Indianola, in the county of Warren and 5 State of Iowa, have invented a certain new and useful Trunk-Filler, of which the following is a specification.

The object of my invention is to provide a trunk filler of simple, durable and inexpensive construction.

A further object is to provide such a device so constructed and arranged that it may be readily and easily expanded longitudinally, laterally and vertically to occupy the 15 unfilled space in a trunk or the like.

My invention consists in certain details, in the construction, combination and arrangement of the various parts of the device, whereby the objects contemplated are 20 attained; as hereinafter more fully set forth, pointed out in my claims and illustrated in the accompanying drawings, in which—

Figure 1 shows a top or plan view of a trunk filler, embodying my invention. Fig. 25 2 shows a vertical, central, sectional view through said trunk filler, and Fig. 3 shows a sectional view through one of the adjustable locking devices. Fig. 4 shows a longitudinal, vertical, sectional view through the 30 sleeve and the ends of two of the connecting rods.

My improved trunk filler comprises two rectangular frames, each comprising two horizontal side members and two horizontal 35 end members. The side members of the upper frame are composed of two parts 10 and 10^a, slidably connected in a manner hereinafter described and the end members of the upper frame are each composed of two parts 40 11 and 11^a, slidably connected in the manner hereinafter described. The horizontal side members of the lower frame are each comprised of members 12 and 12^a, slidably connected, and the end members of the lower 45 frame are each comprised of members 13 and 13^a, slidably connected. The members 10 and 10^a, 12 and 12^a, 11 and 11^a and 13 and 13^a are slidably connected in the same way and I shall describe the construction for 50 thus connecting them for the members 10 and 10^a only. At their adjacent ends, the members 10 and 10^a are formed with cut-away portions 14, designed to receive the extensions 15 and 16 on the members 10^a

and 10, as clearly shown in Fig. 1. Secured 55 to the outer or free end of the extension 15 is a guide device 17 in which the extension 16 slides freely, and secured to the outer end of the extension 16 is a similar guide 17 in which the extension 15 slides freely. I preferably provide flat reinforcing strips 18 for connecting the horizontal members at the corners of the device.

For sliding the ends of the device longitudinally away from or toward each other, 65 I have provided the following means above the upper and lower frames. Extending inwardly from the members 11^a are rods 19, which at their inner ends are provided with right and left hand screw threads. The inner ends of the rods 19 are received in a sleeve 20, which is internally screw threaded so that when rotated in one direction it turns both of the rods 19 outwardly and when rotated in another direction it draws 75 both of the rods 19 together. Formed on the sleeve 20 is a corrugated rib 21 for more easily rotating the sleeve 20.

Connecting the respective members 11, the respective members 13 and the respective 80 members 13^a are similar rods 19 and similar sleeves 20, shown in Figs. 1 and 2. Connecting the members 10^a with each other, the members 10 with each other, the members 12^a with each other and the members 12 85 with each other are similar rods 19 and sleeves 20, shown in Figs. 1 and 2. It will thus be seen that either of the horizontal frames may be contracted or expanded by rotating the various sleeves 20 to force the 90 opposite sides or ends of said frames apart or draw them together. The upper frame is mounted above the lower frame and spaced apart therefrom by the following means: Extending upwardly from the corners of the lower frame are cylinders 22, and extending downwardly from the corners of the upper frame are cylinders 23 telescopically received within the cylinders 22. I 95 preferably use braces 24, extending from 100 points near the upper ends of the members 22 downwardly and inwardly to the members 12 and 12^a, as shown in Fig. 2.

For locking the braces 22 and 23 in various positions of their telescopic movement 105 with relation to each other, I have provided the following means: In the walls of the cylinders 23 I form a plurality of openings

25. Extending inwardly from the upper end of each cylinder 22 is a small cylinder 26 in which is slidably mounted a stem 27 which extends outwardly through the opening 28 and the closed end 29 of the cylinder 26. Formed on the stem 27, near the inner end thereof, is a circumferential annular flange 30^a. On the stem 27, within the cylinder 26 and between the flange 30^a and the closed end 29 of said cylinder is an extensible coil spring 30, designed to hold the stem 27 at the inward limit of its movement. Formed on the cylinder 26 is a laterally extending lug 31. On the outer end of the stem 27 is a head 32. Formed on the head 32 is an arm 33, so constructed and arranged that when the stem 27 is drawn outwardly and rotated to one position of its movement the arm 33 will engage the lug 31 and prevent the inward movement of the stem 27. In other positions of the rotation of the stem 27, the arm 33 clears the cylinder 26 and allows the spring 31 to force the stem 27 to the inward limit of its movement. The inner end of the stem 27 is designed to selectively enter one of the openings 25 for locking the cylinders 22 and 23 in various positions of their adjusted movement. On the upper surfaces of the members 12 and 12^a I 30 secure tacks 34 or other fastening devices. When the filler has been adjusted as desired, the cords 35 may be secured to the tacks 34, extended around the members 12 and 12^a and stretched between them to keep clothing or 35 other articles from extending within the outline of the filler.

It will be understood that various kinds of materials may be used in the construction of my device and that changes may be 40 made in the details of the construction and it is my intention to cover by this application any changes in construction that may come within the scope of the appended claims.

45. In the practical operation of my improved trunk filler the device may be placed in position shown in Fig. 1, on top of the contents of a partly filled trunk or it may be placed on its side in one side of a partly 50 filled trunk. The adjustability of the device longitudinally and laterally is designed largely for the purpose of being able to adjust the device for trunks of various sizes. The greater vertical adjustment is 55 designed for the purpose of filling the empty part of the trunk. Assuming that the trunk is partly full, the filler may be placed on top of the contents and by rotating the sleeves 20 the device may be lengthened and 60 widened to substantially fit the trunk. The stems 27 may then be withdrawn and rotated until the extensions 33 engage the lugs 31. The cylinders 33 may then be slid upwardly until the trunk is full when the 65 stems 27 may be again rotated until the ex-

tensions 33 clear the lugs 31 and the cylinders 26, and the ends of the stems 27 enter the upper openings 25.

The advantage of such a device in filling the unfilled space in a trunk so that the 70 contents thereof cannot be jarred about will be obvious from the foregoing description.

I claim as my invention:

1. In a device of the class described, two rectangular frames, each comprising end members composed of two parts, slidably connected, side members composed of two parts slidably connected, means for adjustably securing the respective parts of the side members in any position of their sliding movement, said means comprising two pairs of rods arranged in alinement with each other, the respective members on each pair being secured to one part of each end member, the adjacent ends of said rods being oppositely screw threaded, an oppositely screw threaded cylinder on said ends, means for securing the respective end members in any position of their sliding movement, said means comprising two pairs of rods, the rods of each pair being arranged in alinement with each other and secured to parts of said side members, the adjacent ends of said rods being screw threaded in opposite directions, and internally screw-threaded cylinders received on said screw threaded ends, upright corner posts connecting the corners of the respective frames, said corner posts being made in two parts telescopically connected, the inner posts being provided with a plurality of holes, a laterally extending casing on each outer post, a bearing, a spring actuated stem therein designed in one position of its movement to selectively enter one of said holes, said stem extending outwardly through said casing and provided with a head, a lug on said casing, a lug on said head designed in one position of the rotary movement of said stem to engage said first lug and hold the stem away from said post. 110

2. In a device of the class described, two rectangular frames, each comprising end members composed of two parts, slidably connected, side members composed of two parts slidably connected, means for adjustably securing the respective parts of the side members in any position of their sliding movement, said means comprising two pairs of rods arranged in alinement with each other, the respective members on each pair being secured to one part of each end member, the adjacent ends of said rods being oppositely screw threaded, an oppositely screw threaded cylinder on said ends, means for securing the respective end members in any position of their sliding movement, said means comprising two pairs of rods, the rods of each pair being arranged in alinement with each other and secured to parts of said side members, the adjacent ends of said rods being 115

120

130

screw threaded in opposite directions, internally screw threaded cylinders received on said screw threaded ends, upright corner posts connecting the corners of the respective frames, said corner posts being made in two parts telescopically connected, and means on each post for locking the parts

thereof in various positions of their slidable adjustment.

Des Moines, Iowa, March 18, 1913.
